UNITED STATES PATENT OFFICE

FREDERICK GEIGER, OF CLEVELAND, OHIO, ASSIGNOR TO THE ENAMEL PRODUCTS COMPANY, OF CLEVELAND, OHIO, A CORPORATION OF OHIO

DRAIN BOARD

Application filed January 4, 1928. Serial No. 244,415.

The present invention, as indicated, relates to adjustable supports for drain boards and the like, and more specifically to means for supporting enameled sheet metal drain boards. The primary object of the invention is to provide a support of the type indicated which will permit proper location of the drain board with respect to the wall or the backboard of a sink, and which will further be adjustable to maintain a proper tension upon the drain board itself to prevent buckling. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a bottom plan view of a drain board equipped with an extensible clamp of the type contemplated by the present invention; Fig. 2 is a transverse section taken substantially on the line 2—2 of Fig. 1; Fig. 3 is a vertical section taken substantially on the line 3—3 of Fig. 2; and Fig. 4 is a fragmentary section taken substantially on the line 4—4 of Fig. 3.

Referring more particularly to the drawings, the reference numeral 1 indicates a drain board formed of enameled sheet metal. Said drain board is adapted to be attached to a wall 2 and to abut against the front surface of a backboard 3 of a sink (not shown). The drain board 1 is provided with laterally depending flanges 4 and 5 which are inturned at their bottom edges to form lips 6 and 7, respectively. A bracket 8 is secured to the wall 2 by means of screws 9 or similar fastening means, and said bracket carries upwardly projecting bolts 10 and 11.

The extensible clamp whereby the drain board is secured to the bracket comprises a relatively long strip 12 formed with longitudinally extending slots 13 and 14. One end of the strip 12 is bent at right angles to

the major portion of the strip to form a lug 15 provided with a screw-threaded aperture 16. It is to be understood, of course, that this lug 15 might as well be a separate member attached to the strip 12, but I prefer, for reasons of economy and efficiency, to form said lug integrally with the strip 12. A second, relatively short strip 17 has one end bent at right angles to form a lug 18 similar to the lug 15, said lug 18 being provided with a screw-threaded aperture 19. A double ended screw, indicated generally at 20, is provided with right hand threads on its one end 21, and with left hand threads at its other end 22. Intermediate the two ends 21 and 22 there is formed a polygonal portion 23 which is adapted to be engaged by a wrench. The end 21 of the screw 20 extends into the aperture 19 in the lug 18, while the end 22 thereof extends into the aperture 16 of the lug 15.

The free end 24 of the strip 12 abuts against a block 25 of rubber or similar resilient material which is retained against the flange 5 by the lip 7, and the free end 26 of the strip 17 abuts against a similar block 27 held against the flange 4.

The two strips 12 and 17, having been adjustably secured to each other by means of the screw 20, are inserted between the blocks 25 and 27, and the screw 20 is rotated to force the strips 12 and 17 apart, whereby the clamp will exert the desired tensioning force on the drain board. The strip 12 is then mounted on the bracket 8 with the bolts 10 and 11 extending through the slots 13 and 14, respectively, and the drain board 1 is brought into the desired relation with respect to the wall 2 or backboard 3 by shifting said board toward or away from the wall. When the board has been brought into the desired position, the nuts 28 are turned down on the bolts 10 and 11 to secure the clamp and board rigidly in place. The polygonal portion 23 of the screw may be provided, if desired, with sockets 29 for the reception of a bar to be used in turning said screw.

Other modes of applying the principle of my invention may be employed instead of the one explained, change being made as regards

the mechanism herein disclosed, provided the means stated by any of the following claims or the equivalent of such stated means be employed.

5. I therefore particularly point out and distinctly claim as my invention:

1. The combination with a drain board, of supporting means therefor comprising a relatively long strip formed with a plurality of longitudinally extending slots therethrough, a bracket, means adapted to coact with said bracket and to pass through said slots to secure said strip to said bracket, and a second relatively short strip adjustably secured to 15 said first strip, the free ends of said strips engaging said drain board to support the same.

2. The combination with a drain board, of supporting means therefor comprising a relatively long strip formed with a plurality 20 of longitudinally extending slots therethrough, a bracket, means adapted to coact with said bracket and to pass through said slots to secure said strip to said bracket, an angularly projecting lug on one end of said 25 strip and provided with a screw-threaded aperture, a second relatively short strip provided at one end with an angularly projecting lug formed with a screw-threaded aperture, and a right-and-left-hand screw having one 30 end engaged in each of said apertures and adjustably securing together said strips, the free ends of said strips engaging said drain board to support the same.

3. As a new article of manufacture, an adjustable clamp comprising a relatively long strip formed with a plurality of longitudinally extending slots therethrough, and having one end bent at right angles to form a projecting lug, said lug being formed with a 35 screw-threaded aperture, a second relatively short strip having one end bent at right angles to form a projecting lug, said lug being formed with a screw-threaded aperture, and a right-and-left-hand screw having one 40 end engaged in each of said apertures, and adjustably securing said strips to each other.

4. The combination with a sheet-metal board having a depending flange on each of 50 two opposite sides, of a clamp therefor comprising a pair of metal strips, an upstanding apertured ear on each of said strips, the apertures of said ears being oppositely threaded, and a right-and-left-hand screw having its opposite ends engaged in said 55 respective apertures the free ends of said strips engaging said flanges.

5. The combination with a sheet-metal board having a depending flange on each of 60 two opposite sides, of a clamp therefor comprising a metal strip having one end bent at right angles to form an upstanding ear, a second metal strip having one end bent at right angles to form an upstanding ear, 65 means securing said ears to each other and

operable to move said strips toward or away from each other, and resilient means interposed between the opposite ends of said strips and said flanges, respectively, and adapted to transmit pressure from said strips to said flanges.

6. The combination with a drain board, of supporting means therefor comprising a bracket, an extensible clamp secured to said drain board, and means for mounting said clamp on said bracket.

7. The combination with a drain board having a depending flange on each of two opposite sides, of supporting means comprising a bracket, an extensible clamp adapted to exert pressure against said flanges, resilient means interposed between said clamp and said flanges, and means adjustably securing said clamp to said bracket.

Signed by me this 28th day of December, 1927.

FREDERICK GEIGER.
